CLAIM

The ornamental design for a folding hatchet, as shown and described.

DESCRIPTION

FIG. 1 is a elevational view of a folding hatchet showing my new design;

FIG. 2 is a top plan view thereof;

FIG. 3 is a bottom plan view thereof;

FIG. 4 is a side elevational view thereof with the hatchet shown in the folded position; and

FIG. 5 is a perspective view thereof with the hatchet shown in the unfolded or open position.

FIG. 5
